UNITED STATES PATENT OFFICE.

CARL MARTIN, OF KEARNY, NEW JERSEY, ASSIGNOR TO GENERAL ELECTRIC COMPANY, A CORPORATION OF NEW YORK.

SEALING-OFF DEVICE.

Application filed June 4, 1923. Serial No. 643,182.

The bulbs of incandescent lamps and similar evacuated devices are exhausted through an exhaust tube and sealed by heating the exhaust tube to fusion near the bulb, there-
5 by hermetically sealing the bulb and at the same time detaching it from the tube. This operation of sealing off has usually been done by automatic devices, which sealed off the bulb, but from which the sealed bulb
10 must be removed by hand. These devices usually consist of rather complicated mechanism which occupies considerable space upon the table of the exhaust machine.

One object of my invention is to provide
15 an automatic sealing off device which will automatically seal off a bulb and also automatically discharge or eject the sealed off bulb from the sealing off device. Another object is to simplify and improve the mechanism of the sealing off device so that minimum space on the table of the exhaust machine will be required. A further object is in general to simplify and improve automatic devices of this character.

25 In carrying out my invention I provide an automatic sealing off device with means automatically operative at the conclusion of the sealing off operation for ejecting or discharging the sealed off bulb. In a desirable form of my invention the bulb fork or holder is given a movement along the exhaust tube to effect the sealing off operation, and subsequently an additional movement to eject the bulb from the bulb holder.
30 This additional movement for ejecting the sealed off bulb is preferably, though not necessarily, a continuation of the sealing off movement, and is produced by some means or mechanism which operates subsequent to the completion of the sealing off movement of the device. The actuating mechanism is simplified and space on the table is saved by giving to the bulb fork a vertical sealing off movement only thereby eliminating the mechanism required to move the fork horizontally. The sealing off device may to advantage be actuated directly from the exhaust spider which carries the bulbs to be exhausted.

50 My invention will best be understood in connection with the accompanying drawing in which Figure 1 is a side view of one form of my sealing off device with certain parts in section; Figure 2 is a view at right angles to the plane of Figure 1 show-

ing the bulb engaging parts of the device in their initial position prior to engaging the bulb; Figure 3 is a similar view of the same parts in engagement with the bulb at the beginning of the sealing off operation; Figure 4 is a similar view of the same parts after the bulb has been moved slightly to draw a contraction in the heated exhaust tube; Figure 5 is a similar view of the same parts at the conclusion of the sealing off operation; Figure 6 is a view showing the position of the parts when automatically discharging the sealed off bulb; Figure 7 is a side view of the sealing off device operated by a cam instead of by compressed air, and in a position corresponding to Figure 2; Figures 8, 9, 10 and 11 are side views of the same device in position corresponding to Figures 3, 4, 5 and 6, and Figure 12 is a plan view of the device shown in Figure 9.

The exhaust machine of the usual type as shown in United States patents to Massey 996,936 and to Burrows 1,013,124, comprises a table 1 with intermittent gearing 2 for imparting a step by step movement to a rotatable exhaust spider 3 provided with exhaust tube holder or heads 4 of the usual type. Each head or holder receives the exhausted tube 5 of a lamp 6 which is to be exhausted and as the spider 3 rotates each lamp is automatically connected in succession to the various pumps through the flat valve on which the spider 3 is carried. The exhausted lamp is sealed off while it is stationary in the position indicated in dotted lines in Figure 1.

The sealing off device comprises a movable bulb fork 7 for lifting or pulling the bulb away from the exhaust tube during the sealing off operation. This bulb fork is hinged or pivoted, and has a tail 8 for tilting it about the pivot 8^a by means of which it is hinged on a pivoted arm 9 which in turn is pivoted on a vertically movable head 10. The bulb fork cannot swing below the horizontal because of a stop such as a threaded stud 11 set in the head 10 to project through a hole in the arm 9 somewhat larger than the shank of the stud. The head of the stud is considerably larger than the shank and acts as a stop to limit the counterclockwise movement of the arm 9 and therefore the downward movement of the fork 7. The arm 9 and fork 7 are yieldingly held in the po-

sition shown in Figure 2 by a spring 12. The head 10 is moved vertically by some suitable mechanism, such as a vertically reciprocating piston rod 13 having a piston 14 in a cylinder 15 which stands upright on the table 1 of the exhaust machine, which automatically moves the bulb fork to pull the bulb away from the exhaust tube. The upper end of the cylinder constitutes a dash 10 pot which controls the upward movement of the head 10 and the bulb fork 7 and which is regulated by an adjustable vent valve 15'. A compression spring 16 may be placed beneath the piston 14 to store up energy and 15 to assist in raising the bulb fork 7 into contact with the bulb 6. To impart an additional upward movement to the head 10 after the sealing off operation is concluded I provide some means for positively moving 20 the head 10 to the extreme limit of its upward travel. In the particular device shown this additional positive movement is obtained by admitting compressed air into the cylinder 15 below the piston 14 through a port 25 17 in the tubular lower end of the piston rod 13 supplied with compressed air through a flexible connection such as a rubber tube 18. Compressed air is admitted to and exhausted from the cylinder 15 by a valve 19 which is automatically actuated by a cam 20 on the driving mechanism when the valve 19 is closed, a piston 19^a on the valve stem uncovers exhaust ports 19^b, as shown in Fig. 1, thereby exhausting the air from the tube 18 and cylinder 15. When the valve 19 is open to admit compressed air to the cylinder 15 the piston covers the exhaust ports. The sealing off device is actuated during the sealing off operation by energy stored 40 in an energy storing mechanism such as a spring or weight. The energy is stored up during the movement of the spider 3 to carry an exhaust head 4 into the sealing off position. In the particular device shown 45 the spider 3 sets the energy storing mechanism through pins 21 which project from the exhaust heads 4 and depress one end of a pivoted lever 22, the other end of which rises and actuates a pivoted lever 23 connected through a link 24 to the head 10. The free end of lever 23 carries a weight 25, which is lifted as the mechanism is set. The sealing off mechanism is set, as best 55 shown in Figure 1, while the lamp is approaching the sealing off position. The pin 21 on the exhaust head in front of the one which holds the lamp to be sealed off encounters and presses down the lever 22, thereby lowering the head 10 and bulb fork 60 into the initial position shown in Figure 2, and at the same time storing energy by compressing the spring 16 and lifting the weight 25. As the lamp to be sealed off comes into the sealing off position shown in dotted lines 65 with the bulb immediately above the bulb fork, the pin 21 passes off the end of the lever 22, whereupon the sealing off device is released, and the bulb fork is raised by the spring 16 and the weight 25 at a rate dependent upon the setting of the vent valve 15'. The bulb fork encounters the bulb and swings the arm 9 on its pivot, stretching the spring 12, until the arm encounters the stop 11 as shown in Figure 3, thereby rendering the bulb fork in effect a rigid extension of the head 10. The full upward thrust of the head 10 is now exerted on the bulb and is resisted by the exhaust tube, which is held by the exhaust head or holder 4, now stationary in the sealing off position of the lamp. As this exhaust tube is heated at a point adjacent the fork by some means, such as the burners 26 preferably mounted on the head 10, the glass softens until finally it yields and the head 10 moves upward slightly into its intermediate position shown in Figure 4, thereby drawing a contraction in the exhaust tube. The head 10 has now, due to the adjustment of the energy storing means, reached the limit of its sealing off movement. As the flames of the burners 26 continue to play upon the contraction in the exhaust tube the glass of the exhaust tube melts, thereby hermetically sealing the bulb and also freeing it from the exhaust tube, whereupon the spring 12 contracts and swings the arm 9 and fork 7 with the sealed off bulb in it into the position shown in Figure 5. The bulb is now sealed off and completely separated from the exhaust tube. The sealed off bulb may be automatically discharged from the bulb fork 7 by various means acting automatically at the conclusion of the sealing off operation. One simple and satisfactory way of automatically discharging the sealed off bulb is to tilt the fork about its pivot at the conclusion of the sealing off operation and thereby swing it into the position shown in Figure 6 so that the bulb is discharged by gravity. The fork may be moved or tilted in various ways to discharge the sealed off bulb, but I prefer to provide some means for positively actuating or tilting the fork by the driving mechanism of the exhaust machine. I prefer that the means for tilting the bulb fork and thereby discharging the sealed off bulb be constructed so as to impart to the tail 8 of the bulb fork and a cooperating member a relative movement which will bring them into contact and positively tilt the fork. A convenient way to do this is to impart an additional upward movement to the head 10, and thereby, as best shown in Figures 5 and 6, bring the tail 8 of the fork into operative relation to some means, such as an adjustable stationary stop 27 which tilts the bulb fork 7 in response to the further movement of the head 10 from the position shown in Figure 5, where the sealing 105 110 115 120 125 130

off operation is completed, into the position shown in Figure 6, where the bulb fork is tilted so much as a result of the cooperation of the fork tilting stop 27 and the actuating mechanism for the head 10 that it is out of the path of the exhaust tube in the holder and the sealed off bulb will automatically fall or be discharged into the discharge chute 28. This additional or extra movement is a positive movement imparted to the reciprocating member or head 10 through actuating means driven either directly or indirectly by the driving mechanism of the machine. For example, the bulb fork may be tilted by actuating the member 10 by admitting compressed air to the cylinder 15 at the proper time through the valve 19 controlled automatically by the cam 20 on the driving mechanism. After the sealed off bulb is discharged the valve 19 closes, the compressed air is exhausted from the cylinder 15 and the bulb fork 7 and other parts drop back by their own weight to the normal position shown in Figure 5. As the head 10 begins to move down, carrying the bulb fork 7 with it, the bulb fork is thrown back toward the horizontal position, preferably by the stop 27, which encounters some part of the descending bulb fork, such as the return finger 27^a adjacent tail 8, and positively moves the fork counterclockwise out of its discharge position. This form of device using compressed air has the advantage that it is practically self-contained and can be installed on any exhaust machine very easily, as the cylinder 15 may be set on top of the table 1 of the exhaust machine and the cam 20 may be placed anywhere on the driving mechanism.

The bulb fork may also be actuated and tilted by mechanical connections direct to the driving mechanism, as shown in Figures 7 to 12. The head 10 with the bulb fork is mounted on the upper end of a vertically reciprocating rod 29 which is pulled down into the position shown in Figure 7 by a pivoted arm 30 connected at one end to the rod 29 and actuated by a cam 31 which rotates in a clockwise direction. This cam has a high point to move the rod to its lowest position, shown in Figure 7, and thereby bring the bulb fork into the position of Figure 2. As the cam 31 rotates in a clockwise direction, it permits the rod 29 and the bulb fork to rise in succession into the positions of Figures 8, 9 and 10 which correspond to Figures 3, 4, and 5, and thereby seal off the bulb. At the conclusion of the sealing off operation a recess 32 in the cam 31 permits the additional upward movement of the rod 29 which tilts the fork, as shown in Figure 11, and discharges the bulb. To insure the tilting of the bulb fork I provide the cam with a shroud 33 which will, if necessary, positively actuate the arm 30 to

give the rod the necessary additional movement. The rod 29 is moved upward by energy stored in some energy storing means, such as a weight 34 which is lifted, or a spring 35 which is compressed as the cam 31 moves the rod 29 downward. The rate and extent of upward movement of the rod 29 is dependent on the strength of the energy storing means and the viscosity of the heated glass of the exhaust tube, and is limited by the cam 31. If the spring 34 is made strong enough the weight 34 is unnecessary.

By my invention the bulb fork of the sealing off device moves vertically and is automatically set just prior to the arrival of the lamp at the sealing off position. The upward movement of the fork into engagement with the lamp bulb and during the sealing off operation is controlled by a dash pot or a cam, but is caused by a spring or weight and is dependent upon and regulated to a large extent by the viscosity of the glass of the heated exhaust tube. At the conclusion of the sealing off operation an additional movement is imparted to the bulb holder to automatically deliver the sealed off bulb to a delivery chute or other suitable carrier.

What I claim as new and desire to secure by Letters Patent of the United States, is:

1. In a device for automatically sealing off a bulb from an exhaust tube comprising a movably mounted bulb fork, means adjacent said fork for heating an exhaust tube, means for automatically moving said fork to pull the bulb away from the exhaust tube sufficiently to seal it off, and means for subsequently tilting said fork to discharge the sealed off bulb from the fork.

2. In a device for automatically sealing off a bulb from an exhaust tube the combination of a movably mounted bulb fork, an exhaust tube heater, adjacent said fork to heat the exhaust tube near the bulb, fork actuating mechanism for moving said fork to pull the bulb away from the exhaust tube to an extent sufficient to seal off the bulb, and then further moving said fork and means responsive to said further movement for discharging the sealed off bulb automatically.

3. In a device for automatically sealing off a bulb from an exhaust tube, the combination of a pivotally mounted bulb fork, a heater adjacent said fork to heat the exhaust tube near the bulb, means for moving said fork bodily to pull the bulb away from the exhaust tube sufficiently to seal it off, and means for subsequently tilting said fork on its pivot to discharge the sealed off bulb from the fork.

4. In a device for automatically sealing off a bulb from an exhaust tube, the combination of a reciprocating member, a bulb fork pivotally mounted on said member, an exhaust tube heater adjacent said fork to heat the exhaust tube near the bulb, means

- for imparting to said member a movement sufficient to pull the bulb away from the exhaust tube and thereby seal off the bulb and for then imparting a further movement to said member, and means responsive to said further movement for tilting said fork to discharge the sealed off bulb by gravity.
5. In a device for automatically sealing off a bulb from an exhaust tube, the combination of a movable member, a bulb fork on said member, a heater for softening the exhaust tube adjacent said fork, means for imparting to said member a movement sufficient to pull the bulb away from the exhaust tube and seal it off, and means responsive to further movement of said member for automatically discharging the sealed off bulb from the bulb fork.
6. In a device for automatically sealing off a bulb from an exhaust tube, the combination of a movable member, a bulb fork mounted on said member, a heater for softening the exhaust tube adjacent said fork, means cooperating with said fork at the end of the travel of said member to discharge the sealed off bulb automatically, and actuating means for first moving said member to an intermediate point to cause said fork to pull the bulb away from the exhaust tube sufficiently to seal it off, and subsequently moving said member to the end of its travel to discharge automatically the sealed off bulb from the fork.
7. In a device of the character described the combination of an intermittently movable holder for the exhaust tube of a bulb, a member mounted to reciprocate to one side of the path of the exhaust tube in said holder and parallel to said exhaust tube, a bulb fork mounted on said member to project into the path of movement of the exhaust tube with its open end toward the oncoming exhaust tube, means for heating the exhaust tube adjacent said fork, and actuating means for reciprocating said member to bring the bulb fork into engagement with the bulb and pull the bulb away from the exhaust tube sufficiently to seal it off and for imparting further movement in the same direction to said member, and means responsive to said further movement to automatically discharge the sealed off bulb from the fork.
8. In a device of the character described the combination with a holder intermittently movable horizontally, and adapted to hold the exhaust tube of a bulb vertically, a bulb fork mounted to reciprocate vertically in alignment with said holder when stationary in sealing off position and with its open end toward the oncoming exhaust tube holder, a heater for softening the exhaust tube adjacent said bulb fork, means responsive to the movement of said fork into its uppermost position to automatically discharge a sealed off bulb from the fork and actuating means operating in synchronism with said holder for automatically lowering said fork out of the path of the bulb as the exhaust tube holder moves into sealing off position, then while the exhaust tube holder is stationary in sealing off position raising the fork to an intermediate position to pull the bulb away from the exhaust tube sufficiently to seal it off, and then raising the fork to its uppermost position and thereby automatically discharging the sealed off bulb.
9. In a device of the character described the combination with an intermittently rotatable exhaust tube holder movable horizontally, a bulb fork mounted to reciprocate vertically in the path of movement of the exhaust tube holder, a heater for softening the exhaust tube adjacent said fork, energy storing means connected to said fork and tending when set to move said fork upward, and thereby pull the bulb away from the exhaust tube sufficiently to seal it off and connections between said holder and said fork to depress said fork during the movement of said holder into the sealing off position and thereby set said energy storing means, and to release said fork while said holder is stationary in sealing off position, and means for imparting to said fork an upward movement in addition to that due to said energy storing means to tilt the fork and thereby automatically discharge the sealed off bulb.
10. In a device of the character described the combination of a movable holder for the exhaust tube of a bulb, a member, mounted to reciprocate transversely to the direction of movement of said holder and along the exhaust tube in said holder, a bulb fork on said member, a burner for heating the exhaust tube adjacent said fork, and actuating means for first moving said member to bring the bulb fork into engagement with the bulb to pull the bulb away from the exhaust tube sufficiently to seal it off and for then imparting an additional and further movement in the same direction to said member to carry the fork beyond the sealed off end of the exhaust tube in said holder.
11. In a device of the character described the combination with an intermittently movable holder for the exhaust tube of a bulb, a bulb fork mounted to reciprocate in the path of travel of the exhaust tube and along the exhaust tube, a heater for softening the exhaust tube adjacent said fork, and common actuating means for said holder and said fork for moving said fork out of the way of the bulb as said holder carries it into sealing off position, and for automatically moving the fork along the exhaust tube while said holder is stationary

to pull the bulb away from the exhaust tube sufficiently to seal it off and then imparting an additional and further movement to the fork further to carry it out of the path of travel of the exhaust tube in the holder.

12. A sealing off torch comprising a cylinder, a piston therein having a piston rod projecting through the one end of the cylinder, a bulb fork mounted on the projecting end of said piston rod, a burner mounted to project its flame adjacent said fork, an adjustable vent valve to control the escape

of fluid from the space between the piston and said end of the cylinder, energy storing means tending when set to move said piston toward said end of the cylinders, and means for admitting compressed air to the space between the piston and the other end of the cylinder to impart to the piston a movement additional to that imparted by the energy storing device.

In witness whereof, I have hereunto set my hand this 1st day of June, 1923.

CARL MARTIN.
